C. A. NOYES,
Lathe Slide-Rest,

No. 12,742.

Patented Apr. 17, 1855.

UNITED STATES PATENT OFFICE.

C. A. NOYES, OF PITTSFIELD, MASSACHUSETTS.

SLIDE-REST FOR LATHES.

Specification of Letters Patent No. 12,742, dated April 17, 1855.

To all whom it may concern:

Be it known that I, C. A. NOYES, of Pittsfield, in the county of Berkshire and State of Massachusetts, have invented a new and Improved Slide-Rest for Lathes for Turning Iron; and I do hereby declare that the following is a full, clear, and exact description of the same, reference being had to the annexed drawings, making a part of this specification, in which—

Figure 1 is a plan or top view of a lathe with my improved slide rest applied to it. Figs. 2 and 3 are transverse vertical sections of the lathe (x) (x) Fig. 1, showing the plane of section of Fig. 2 and (y) (y) showing the plane of section of Fig. 3.

Similar letters of reference indicate corresponding parts in the several figures.

The nature of my invention consists in the peculiar construction of the slide rest as will be hereafter shown and described, whereby the edge of the cutting tool may be elevated or depressed with the greatest facility and so as to bring the edge of the cutting tool in a proper relative position or angle with the article to be turned.

To enable others skilled in the art to make and use my invention I will proceed to describe its construction and operation.

A represents the bed of an ordinary lathe and B is a carriage secured to the bed so that it may slide thereon, the same as the carriage of the ordinary slide rest.

C is a sliding box which is fitted into the carriage B in dove tail manner so that said box may be moved forward and backward on the carriage B in a line transversely with the bed A of the lathe. The sliding box is to be operated by a screw in the usual manner.

Within the sliding box C there is placed a small shaft D having a screw E upon it, see Figs. 1 and 3. The screw E gears into a toothed wheel F which is placed within the box C. The wheel F gears into a pinion G also within the box C. The screw E pinion G and shaft D are all secured to the bottom of the box C as clearly shown in Fig. 3.

H is the top of the sliding box C. To the under surface of the top H there are secured bearings (a) (a) in which a small shaft I

fits, said shaft I also passing through the sides of the box C and having a nut (b) at each end. The top H consequently fits between the two sides of the box and rests upon the shaft I, the bearings (a) (a) of which are attached to about the center of the under side of the top. To the under side of the top H there are also secured by pivots (c) (c) which work in proper bearings (d) (d) two nuts (J) (J) one at the front and the other at the back end of the top H, and within each nut a small screw rod K works. Each screw rod has a pinion L upon it, one of which gears into the toothed wheel F and the other into the pinion G.

At the outer end of the shaft D there is secured a small hand wheel M.

To the upper surface of the top H the cutting tool is secured in the usual or any proper manner. The lower ends of the small screw rods K are properly stepped in the bottom of the box C, as shown in Fig. 3.

Operation: The carriage B is moved longitudinally on the bed A by a screw shaft in the usual way and the sliding box C is also moved in a line transversely with the bed A by a screw as in ordinary slide rests. In order to raise or lower the cutting edge of the tool the hand wheel M is turned and the screw E rotates the wheel F which gives motion to the screw rods K K, which rotate or turn in reverse directions owing to the intermediate pinion G, and the top H is consequently inclined as it will rock or turn upon the shaft I, one screw rod K elevating one end of the top, and the other depressing or drawing it down. The cutting edge of the tool therefore may be raised or lowered as desired and brought to bear upon the work at the desired angle, see Fig. 3, in which the circle (a') represents the article to be turned and (b') the cutting tool.

The above invention is extremely simple, will not add materially to the expense of a lathe.

Having thus described my invention, what I claim as new and desire to secure by Letters Patent, is,

Constructing the slide rest as herein shown, viz: having the top H of the sliding

box C rest upon a shaft I and inclining or
tilting said top by means of the screw E,
toothed wheel F pinions L, L, G, screw rods
K, K, and nuts J, J, substantially as herein
5 shown, whereby the edge of the cutting tool
which is secured on the upper surface of the
top H may be raised or lowered as desired

and presented in a proper position to the
article to be turned.

CYRUS A. NOYES.
